THERMALLY INSULATED PICNIC BAG

Moritz Nappe, Farmingdale, N. J.

Application April 18, 1957, Serial No. 45,794

Term of patent 14 years

(Cl. D58—2)

FIG. 1.

FIG. 2.

FIG. 3.

Figure 1 is a side perspective view of a thermally insulated picnic bag shown in closed position and illustrating my new design;

Figure 2 is a top plan view thereof in closed position; and

Figure 3 is a top perspective view thereof, showing the bag in open position with the closure portion folded down about the exterior of the bag to expose the interior thereof.

The side of the bag not shown is the same as the side shown in Figure 1.

The characteristic features of my design for the bag disclosed herein reside in the pattern of ornamentation appearing on the external surface of the bag as shown.

I claim:

The ornamental design for a thermally insulated picnic bag, as shown and described.
